TWEEZERS

George M. Ferguson, Portland, Oreg.

Application October 20, 1944, Serial No. 559,565

3 Claims. (Cl. 81—43)

1

This invention relates generally to tweezers, and particularly to a pair of tweezers of the pincers type.

The main object of this invention is to provide an inexpensive and efficient form of tweezers in which the points will be held in alignment and prevented from opening under excessive pressures.

The second object is to construct a pair of tweezers of the class described which will be easy to manufacture, convenient to hold in the hand, and not easily rendered inoperative.

These and other objects will become more apparent in the specification as illustrated in the accompanying drawing, in which

Fig. 1 is a plan of the device.

Fig. 2 is a side elevation.

Fig. 3 is an enlarged side elevation showing the pivot end of the device.

Fig. 4 is a view similar to Fig. 3, but showing the side disc removed.

Fig. 5 is a transverse section taken along the line 5—5 in Fig. 3.

Fig. 6 is a fragmentary plan of the pivot end of one of the tweezer blades.

Fig. 7 is a perspective view of the completed instrument.

Similar numerals refer to similar parts throughout the several views.

Referring in detail to the drawing, there is shown, by way of example only, a pair of tweezer arms 10, preferably widened at the intermediate points 11 where power is applied, and of sufficient thickness to avoid the necessity of reforming the cross section, to avoid separation of the points 12 when a considerable amount of pressure is applied to the device. Obviously, the members 10 should be made of a high grade tempered steel. The ends 13 are somewhat narrower than the intermediate point 11, and whereas they are commonly joined by riveting or welding, I prefer, in this instance, to unite them by means of a novel construction which will provide the utmost flexibility for the arms 10, accuracy of alignment and ease of manufacture.

I accomplish this by forming on the ends 13, the pivot points 14, which may be square or rounded as desired. The portions 13 of the arms 10 are preferably straight, as illustrated, and are held in spaced relationship by the resilient cylindrical member 15 provided with slots 16, which receive the ends 13 and have a central hole 17 adapted to receive a rivet 18, whose reduced ends 19 extend beyond the ends of the member 15. At each end of the member 15 is placed a side disc 20, provided with a counter sunk opening 21 at the center thereof, and the smaller openings 22 for the pivots 14 of the members 10.

To assemble the device, the members 10 and

18 are inserted in the resilient member 20, which is preferably made of rubber or its equivalent, and the discs 20 are put into place and riveted and the device is ready for use. It will be noted that when pressure is applied to urge the points 12 together, it compresses the material 23 of the bushing 15 between the portions 13 and stretches the material of the members 15 on the opposite side of the rivet 18. The exact position of the pivots 14 with relation to the center line of the rivet 18 will be determined by the resiliency of the member 15, the strength of the members 10 and the character of the service for which the device is intended.

15 It can be seen from the foregoing that while there is provided an ideal pivotal condition, there is also obtained the very desirable result of having the points 12 held in perfect register by means of the side discs 20, which are in close contact with the side edges 24 of the members 13.

While I have referred to the member 15 as resilient and it is preferable that it should be so, it will be apparent that it could be of hard rubber or metal, in which case reliance is placed upon the members 10 for resiliency without departing from the spirit of this invention.

While I have thus illustrated and described my invention, it is not my desire to be limited to the precise form shown herein, and I intend to cover such forms and modifications of the invention as fall fairly within the appended claims.

I claim:

1. In a device of the class described, a combination of a cylindrical rubber insert having a 35 pair of parallel longitudinal slots formed in one side thereof on opposite sides of its center, a tweezer arm occupying each of said slots and having outwardly extending pivot pins between the arm ends projecting beyond the endmost 40 limits of the rubber insert, a disc disposed at each end of said insert having openings therein for the reception of said pivots, and a rivet passing through said discs and through said insert.

2. The device as described in claim 1, characterized by having said discs and insert of the same diameter, said diameter exceeding the outermost spacing of the adjacent ends of said tweezer arms.

3. A device of the class described, consisting 50 of a pair of spaced discs, a cylindrical rubber insert disposed between said discs, said insert having parallel slots formed therein opening on the same side of said insert, tweezer arms having their ends occupying said slots and having pivots 55 projecting therefrom between the arm ends anchoring in said discs and a rivet extending through said discs and rubber insert adapted to hold said discs against the sides of said tweezer arms.

GEORGE M. FERGUSON.
